Des. 223,737
Patented May 30, 1972

223,737

HAIR SPRAY SHIELD

Eva North Smith, 2104 E. Stop 12 Road, Apt. C,
Indianapolis, Ind. 46227

Filed Nov. 27, 1970, Ser. No. 26,199

Term of patent 14 years

Int. Cl. D28—03

U.S. Cl. D86—10

Fig. 1.

Fig. 2.

Fig. 3.

Fig. 4.

Fig. 5.

FIG. 1 is a front elevational view of a hair spray shield showing my new design.

FIG. 2 is a left side elevational view thereof.

FIG. 3 is a rear elevational view thereof.

FIG. 4 is a top view thereof.

FIG. 5 is a bottom view thereof.

The appearance of the right side elevation is a mirror image of that shown in FIG. 2 for the left side elevation.

I claim:

The ornamental design for a hair spray shield, as shown and described.
